UNITED STATES PATENT OFFICE.

CHARLES E. BERRY, OF WATERTOWN, MASSACHUSETTS.

DESIGN FOR A WRENCH AND HOSE-SPANNER.

46,424.

Specification for Design.

Patented Sept. 22, 1914.

Application filed July 27, 1914. Serial No. 853,496. Term of patent 14 years.

To all whom it may concern:

Be it known that I, CHARLES E. BERRY, a citizen of the United States, residing at Watertown, in the county of Middlesex and State of Massachusetts, have invented a new, original, and ornamental Design for a Wrench and Hose-Spanner, of which the following is a specification, reference being had to the accompanying drawing, forming part thereof.

The figure is a perspective view of a wrench and hose spanner, showing my new design.

I claim:—

The ornamental design for a wrench and hose spanner, as shown.

CHARLES E. BERRY.
